G. Y. LEE

METHOD OF PRODUCING FORMS

Filed Jan. 12, 1924

UNITED STATES PATENT OFFICE.

GOCK YOUNG LEE, OF SAN FRANCISCO, CALIFORNIA.

METHOD OF PRODUCING FORMS.

Application filed January 12, 1924. Serial No. 635,876.

To all whom it may concern:

Be it known that I, GOCK YOUNG LEE, a citizen of China, and a resident of San Francisco, county of San Francisco, State of California, have invented a new and useful Method of Producing Forms, of which the following is a specification.

This invention relates to methods of producing articles having a shell like formation such as trays, baskets, vases, boxes, hand bags, and similar objects wherein the form only of the shell walls gives the article its particular characteristic, and the nature of the walls give the article its strength.

The objects of my invention are to provide means by which such articles of thin wall or shell structure may be readily formed to any desired shape either of a mechanical or ornamental nature, but principally the latter so as to meet the demand for a great variety of forms for any or all of the articles above mentioned or others which may be adapted to my process.

An example of a form produced according to my invention is shown in Figure 1 of the drawings accompanying this specification, the representation being that of a fancy fruit basket shown in perspective. Figure 2 is a similar view of the frame structure within the walls of the basket and which consists of a piece of wire cloth or netting shaped to the form of the article which it is desired to produce,—in this example, the fruit basket.

Figures 3 and 4 are perspective views of a box and lid made in accordance with my invention, and Figure 5 is an enlarged sectional view of a piece of the wire inner structure of my shell wall construction showing the paper glued to both sides and the finish coating applied to the outside of the paper.

The wire cloth (1) is of course chosen with reference to the work it must perform when embodied within the article, a heavy wire being used for an article such as a large box and a very light wire for a very small, delicate article such as a jewel tray.

After shaping the wire cloth to the exact form of the article, as the basket shown in Figure 1, it may have other pieces of netting or separate wires (2) attached to it to form any auxiliary members on the article, such for instance as the handle (3) in which

the wire (2) is concealed. The wire netting is then covered on both sides with a sheet of paper, or cloth, but preferably soft paper secured by glue or other adhesive. The paper is forced tightly into the meshes of the wire cloth so as to adhere firmly to all the wires as well as to the paper on the other side. After the paper or cloth is pasted to the wire as described, it then receives a finishing coat either of silk or other decorative cloth glued to it, or is completely enveloped in a cementitious plaster to form the shell walls of the article and further hold the wire netting in the shape to which it has been formed.

There are many plastic compounds available which are suitable for forming the walls, but I prefer the putty like compounds used for modeling ornamental devices, and which may be worked into the meshes of the netting from both sides, and if desired given a distinctive surface texture as indicated at (4) in Figures 1 and 3, also formed into any other desirable ornamentation such as the fruit and leaves shown at (5) at the juncture of the handle (3) and the sides (6) of the basket in Figure 1.

If cementitious composition be used it should be of a character which is plastic while being applied and which hardens into a stone like material, thus rendering permanent the shape given the wire netting.

In Figure 5 the construction above explained will be readily understood, (1) is the wire cloth, (7) is the paper glued in place, and (8) is either the composition cementitious coating or the finishing cloth pasted to the paper.

As the object of gluing soft paper to the wire is to fill or bridge the holes between the wires it is obvious that paper on one side only could be used though it would not be so strong, or the wire could be dipped in heavy glue to bridge or partially bridge the gaps with a film of glue, before applying the composition coating, or the composition could be applied to the wire without the paper first being applied to the wire, but the invention is best carried out by the complete construction described.

When the composition coating is used outside of the paper it is allowed to thoroughly harden and is then given one or more coats of paint or varnish to water-

proof it and prevent softening of the composition in case hot water is used in the finished article.

When making articles such as the box 5 shown in Figure 3, the corners of the wire frame, also the juncture of the bottom to the sides need not be soldered, if made of separate pieces of wire netting, for if lightly stitched with stout thread or light wire will 10 be amply strong, as the paper when glued to both sides of the wire in the manner described will thoroughly reinforce the joints and when the composition is applied the article virtually becomes a unitary structure.

15 In contemplating the wire structure of my invention it will be seen to differ from the mere reinforcing of a cement article, for in the latter case the reinforcement does not represent the finished form of the article, nor is it co-extensive with the walls of the article as it does not extend to every remote part but is subservient to the form, whereas with my method the reinforcement actually is the finished form, the paper and other external coatings serving to permanently sustain the form and make it presentable to the eye.

I claim:

1. The method of producing three dimensional shell forms which consists in shaping a foraminous material to the finished form co-extensive therewith and of then securing it in such a condition by the application thereto of a plastic cementitious material for subsequent hardening.
2. The method of producing three dimensional shell forms which consists in shaping wire cloth to the finished form and of then securing it in such a pre-shaped condition 40 by the application of a cementitious coating

to both sides of the wire cloth to form a wall having sides substantially parallel to the two sides of the wire cloth.

3. The method of producing a three dimensional shell like form which consists in bending a sheet of wire cloth to the desired form, applying a plastic cementitious material to both sides of the wire cloth to form a wall, and of unevenly roughening the wall to produce a texture thereon. 45

4. The method of producing forms in three dimensions which consists in shaping a wire cloth to the finished form and co-extensive therewith, gluing a fibrous sheet of material to the wire cloth and applying a finishing coat to the outer surface of the fibrous sheet. 50

5. The method of producing three dimensional shell forms which consist in shaping wire cloth to the finished form, gluing paper to the side of the wire cloth and then covering both sides with a cementitious coating. 60

6. The method of producing three dimensional shell forms which consists in shaping wire cloth to the finished form and co-extensive therewith, gluing paper to both sides of the wire cloth and then covering both sides with a cementitious coating and painting the cementitious coating. 65

7. The method of producing a fruit basket or the like which consists in bending a sheet of wire cloth to the shape of the basket with upwardly extending walls, of connecting opposite walls with a wire loop, and of applying plastic cement to both sides of the wire cloth and the wire loop and allowing the cement to harden. 70 75
